CLAIM

The ornamental design for a lottery ticket dispenser, as shown and described.

DESCRIPTION

FIG. 1 is a front perspective view of a lottery ticket dispenser according to our new design. The dot-dot-dash broken lines represent unclaimed features of the design. The evenly spaced broken lines represent the boundaries of the claim, forming no part thereof;

FIG. 2 is a front elevational view thereof;

FIG. 3 is a perspective view of FIG. 1 with the dot-dot-dash broken lines removed;

FIG. 4 is an enlarged front elevational view thereof;

FIG. 5 is a right side elevational view thereof;

FIG. 6 is a left side elevational view thereof;

FIG. 7 is a top plan view thereof; and,

FIG. 8 is a bottom plan view thereof.

1 Claim, 5 Drawing Sheets
